UNITED STATES PATENT OFFICE

137,294

DESIGN FOR A BEACH SANDAL OR SIMILAR ARTICLE

Walter McMyler, Los Angeles, Calif.

Application January 15, 1944, Serial No. 112,247

Term of patent 14 years

To all whom it may concern:

Be it known that I, Walter McMyler, a citizen of The United States, residing at Los Angeles, in the county of Los Angeles and State of California, have invented a new, original, and ornamental Design for a Beach Sandal or Similar Article, of which the following is a specification, reference being had therein to the accompanying drawing, forming part thereof, in which

Figure 3 is a bottom plan view showing the marginal flange all around the edge of the sandal and the transverse brace within the flanged edge, which brace has a substantially V-shape notch.

I claim:

The ornamental design for a beach sandal or similar article, as shown and described.

WALTER McMYLER.
